United States Patent Office

Des. 178,288
Patented July 17, 1956

178,288

AIRPLANE

Edward J. Horkey, Rolling Hills, and Timothy C. Walton, Santa Monica, Calif., assignors to Pastushin Aviation Corporation, Los Angeles, Calif.

Application August 17, 1954, Serial No. 31,898

Term of patent 14 years

(Cl. D71—1)

Figure 1 is a front perspective view of an airplane showing our new design;

Figure 2 is a perspective view showing the rear of the airplane;

Figure 3 is a top plan view; and

Figure 4 is a side elevational view.

The dominant features of our design are shown in solid lines in the drawing.

We claim:

The ornamental design for an airplane, substantially as shown and described.
